VENDING MACHINE

Percy C. Smith, Chicago, Ill., assignor to John
F. Meyer, Chicago, Ill.

Application April 28, 1934, Serial No. 722,870

2 Claims. (Cl. 240—2)

This invention relates to vending machines.

It is an object of this invention to provide certain improvements in vending machines which are relatively simple and inexpensive in construction and efficient in use.

Another object of the present invention is to provide a new and improved combination illuminating and ventilating unit for the merchandise display compartment of that particular type of vending machines which are popularly known in the coin machine industry as "crane" vending machines.

In this type of vending machine a crane and grab hook are manipulated by the vendee or operator into position to grab and then deliver, a preselected article of merchandise from the display compartment to the player or operator. Heretofore there has been a problem in connection with these machines in securing adequate and proper illumination of the merchandise storage and display compartment without causing the light to glare in the eyes of the player or operator, and prior to the present invention this has not been accomplished, insofar as I am aware.

It is therefore a further object of the present invention to improve the illumination of the article or merchandise storage and display compartment of vending machines of the so-called crane type hereinbefore mentioned in such a manner that the merchandise displaying and storage compartment thereof is adequately, uniformly and properly illuminated without causing a glare in the eyes of the player or operator of the vending machine.

Another object of the invention is to provide an illuminating unit for a vending machine of the crane type which embodies and uses an ordinary standard light bulb and a new and improved parabolic reflector, this unit producing as much as three times the effective illumination in the display compartment of the vending machine as is produced by the elongated tubular show-case lights heretofore used in vending machines of this type.

A further object of the invention is to provide a new and improved combination ventilating and illuminating unit which cannot be removed from the outside of the vending machine and is, therefore, theft-proof.

Additional objects will appear hereinafter.

The invention consists in the novel combination and arrangement of parts to be hereinafter described and claimed.

The invention will be best understood by refer-

ence to the accompanying drawing, showing the preferred form of construction, and in which:

Fig. 1 is a perspective view illustrating a preferred embodiment of the invention in conjunction with a vending machine of the crane type hereinbefore mentioned; 5

Fig. 2 is a top plan view of the vending machine illustrated in Fig. 1 showing the new illuminating unit in conjunction therewith;

Fig. 3 is an enlarged longitudinal, sectional view on line 3—3 in Fig. 4. 10

Fig. 4 is a transverse sectional view on line 4—4 in Fig. 3.

Fig. 5 is a transverse sectional view on line 5—5 in Fig. 3; and 15

Fig. 6 is a side elevational view of one of the new illuminating units.

As has been stated hereinbefore, the present invention contemplates the better, more uniform and glareless illumination of that particular type of vending machine known in the coin machine industry as "crane" machines, and one of the same is illustrated in Fig. 1 of the drawing, wherein it is generally indicated at 10, and comprises an upright cabinet which is of such a height that a person of average height operating or playing the same can readily see into the upper and merchandise displaying and storage compartment 11 thereof, so as to watch the operation of the coin controlled crane 12 and claw 13, by means of which the operator attempts to grab a preselected article of merchandise arranged in the display compartment 11, and if he be successful, the same is delivered or vended to him at the discharge trough or outlet 14, by action of the crane 12 and claw 13. 20 25 30 35

One of the difficulties heretofore experienced in connection with vending machines of this character has been to illuminate the display compartment 11 and the merchandise and operating parts uniformly satisfactorily and adequately and yet not cause the light to glare against the front wall of the display compartment into the eyes of the operator of the vending machine. For this purpose elongated show-case illuminating tubes have been used. These, however, are not satisfactory for a number of reasons, among which are that they are of special construction, they do not illuminate the display or merchandise compartment adequately, and they cause a glare in the eyes of the operator. 40 45 50

To overcome the foregoing and other difficulties experienced in the prior art, and to accomplish the aforementioned and other objects of the present invention, the same provides, in combination, 55

tion with the top wall 15 of the merchandise displaying and vending compartment 11, a new illuminating unit 16; the top wall 15 of the merchandise displaying compartment 11 acting as a support for the new illuminating unit 16, as will appear more fully hereinafter.

The new combination ventilating and illuminating unit 16 comprises a housing 17 in which are arranged a control switch 20 and a standard light receptacle or socket 18, containing a standard light bulb 19 of sufficient wattage to illuminate the display compartment 11 adequately.

The new combination ventilating and illuminating unit 16 also comprises a parabolic reflector 21 which is formed integrally with the housing 17 and includes a substantially annular and vertical side wall 23 that is arranged within an opening 22 formed in the top wall 15 of the display compartment 11; the side wall 23 of the reflector 21 having a downwardly flared visor or depending skirt 24 at its forward edge, and is held in position in the opening 22 of the top wall 15 by means of an annular flange 25 formed on the reflector 21 and which bears upon the upper surface of the top wall 15 of the display compartment 11; the unit 16 being fastened to the top wall 15 of the vending machine by means of screws or the like 28 which are threaded through the top wall 15 of the cabinet into a flange 27 formed on the housing 17; the housing 17 of the new unit being provided with vent holes 29.

The foregoing arrangement of the new combination ventilating and illuminating unit upon, and at the center of the top wall 15, and above the center of the display compartment 11, in the manner shown and described, adequately ventilates the display compartment 11 and the housing 17 and reflector 21, and at the same time the parabolic reflector 21 and its visor 24 diffuse the light from the bulb 19 centrally and uniformly down through the display compartment 11, giving as much as three times the effective illumination of tubular show-case lights, and without the special construction and expense of the latter, while at the same time the depending skirt or visor 24 of the reflector 21 prevents the glare of the bulb 19 from striking the front wall 26 of the display compartment and the operator's eyes, so that the operator of the vending machine and spectators therearound may comfortably watch the operation of the crane 12 and claw 13, and the merchandise arranged in the display compartment 11, and the same are well and uniformly illuminated and displayed to good advantage, and yet the operator of the machine and the spectators do not suffer any discomfort from light glaring in their eyes while operating and watching the vending machine, as has been experienced heretofore in connection with vending machines of the crane type.

The new unit being constructed and mounted as shown adequately ventilates the display compartment 11 and reflector 21 without the necessity for forming other and special holes in the cabinet, the position and location of the same

make it readily accessible only to an authorized person knowing its location, and the unit being mounted in the top wall 15 of the cabinet by the inverted fastening elements or screws 28 cannot be removed from the outside and hence is theft-proof, which is a matter of considerable importance because these machines are usually placed in public places.

While I have illustrated and described the preferred form of construction for carrying my invention into effect, this is capable of variation and modification, without departure from the spirit of the invention. I, therefore, do not wish to be limited to the precise details of construction set forth, but desire to avail myself of such variations and modifications as come within the scope of the appended claims.

Having thus described my invention what I claim as new and desire to protect by Letters Patent is:

1. A vending machine cabinet including a top wall provided with a centrally disposed opening and said cabinet including a display compartment arranged below said top wall and having a transparent front; an electrical illuminating unit for said display compartment including a housing mounted upon the said top wall of said cabinet above the latter; an electric lamp socket in said housing; said housing having a reflector portion arranged in said opening and including a visor or skirt portion projecting downwardly through said opening into said display compartment, and facing toward the said transparent front of the latter; an electric lamp having its base mounted in said socket and having its bulb arranged under the said reflector portion of said housing; and means for mounting the said housing and its said reflector portion upon the said top wall of the cabinet including inverted fastening elements extending upwardly from said display compartment through the said top wall of said cabinet and engaging with said housing.

2. A vending machine cabinet including a top wall having an opening formed therein and said cabinet including a display compartment arranged below said top wall and having a transparent front; an electrical illuminating unit for said display compartment including a housing mounted upon the said top wall of said cabinet above the latter; and electric lamp socket in said housing; said housing having a reflector portion arranged in said opening and including a visor or skirt portion projecting downwardly through said opening into said display compartment, and facing toward the said transparent front of the latter; an electric lamp having its base mounted in said socket and having its bulb arranged under the said reflector portion of said housing; and means for mounting the said housing and its said reflector portion upon the said top wall of the cabinet including inverted fastening elements extending upwardly from said display compartment through the said top wall of said cabinet and engaging with said housing.

PERCY C. SMITH.
